(57) **CLAIM**

The ornamental design for a gaming machine, as shown and described.

DESCRIPTION

FIG. 1 is a perspective view of a gaming machine in accordance with my design;

FIG. 2 is a top plan view of the gaming machine in accordance with my design;

FIG. 3 is a bottom plan view of the gaming machine in accordance with my design;

FIG. 4 is a side elevation view of the gaming machine in accordance with my design;

FIG. 5 is a front elevation view of the gaming machine in accordance with my design;

FIG. 6 is the opposite side elevation view of the gaming machine in accordance with my design; and,

FIG. 7 is a rear elevation view of the gaming machine in accordance with my design.

The broken-line disclosure of elements is understood to represent portions of the gaming machine in which the design is embodied, but which form no part of the claimed design.
